UNITED STATES PATENT OFFICE.

HENRY P. CLAUSEN, OF MOUNT VERNON, AND CHARLES L. GOODRUM, OF NEW YORK, N. Y., ASSIGNORS TO WESTERN ELECTRIC COMPANY, INCORPORATED, OF NEW YORK, N. Y., A CORPORATION OF NEW YORK.

TELEPHONE SYSTEM.

1,343,903.

Specification of Letters Patent. Patented June 22, 1920.

Application filed September 14, 1917. Serial No. 191,356.

To all whom it may concern:

Be it known that we, HENRY P. CLAUSEN and CHARLES L. GOODRUM, citizens of the United States, residing at Mount Vernon, in the county of Westchester and State of New York, and at New York, in the county of New York and State of New York, respectively, have invented certain new and useful Improvements in Telephone Systems, 10 of which the following is a full, clear, concise, and exact description.

This invention relates to telephone systems employing electrically operated switching apparatus for establishing connections 15 between subscribers' lines.

More particularly it relates to a system employing directly actuated switching devices in which a plurality of terminal sections are arranged to be traversed by 20 separate brush sets individual to each section and carried by a common shaft, which is actuated by a single operating mechanism in response to one character of impulse series to position one set of brushes 25 in position to coöperate with its associated section, and in response to a different character of impulse series to position another set of brushes for operation with the section with which it is associated.

30 One of the objects is the provision of means, in connection with a selective switch of the foregoing character, whereby the particular set of brushes appropriated for use in extending a connection is electrically connected to the incoming or calling line. In accordance with a feature of the invention said means includes a plurality of relays with circuits therefor, associated with the switch operating circuits in such a manner as to respond directly to the impulses transmitted from the calling substation to render effective one or another of the brush sets, dependent upon the number of impulses transmitted.

45 A clearer conception of the invention will be had from a consideration of the following description, taken in connection with the accompanying drawing wherein the figure diagrammatically illustrates so much of a 50 telephone system as is necessary to an understanding of the said invention.

Referring to the drawing, 1 represents a subscriber's substation having a calling transmitter 2, by means of which the neces-

sary impulses may be sent over the line to 55 operate the central office switching apparatus in completing a telephone connection with another subscriber. At 3 is shown the line or stepping relay of the selector switch, the circuit of which relay is repeatedly 60 opened and closed each time the impulse sender 2 is manipulated. The selector brush shaft 4 has fastened thereon the two sets of brushes 5, 6, 7 and 8, 9, 10. Brushes 5, 6, 7 are arranged to wipe over the contact terminals of all trunk groups in the lower section of the bank, which, as will later appear, are the even digit groups; and brushes 8, 9, 10 are arranged to make contact with all the groups located in the upper 65 70 or odd digit section of the bank. In the figure only two groups of terminals and a portion of another group are shown to each section. However, it will be understood that in practice several such groups would be 75 provided, the omission being made merely for convenience in the representation of the figure.

Shaft 4 is provided with a rack 11 having on one side thereof, a series of closely 80 spaced ratchet teeth 12, and on its other side a series of more distantly spaced ratchet teeth 13. A primary or group selecting magnet PM has an armature 14, pivoted at 15, and which is provided at its free end 85 with a stepping pawl 16. Upon each energization of magnet PM the consequent attraction of armature 14 causes the pawl 16 to engage one of the teeth 13 to elevate the brush shaft through one long step. For this 90 purpose armature 14 is made comparatively long in order to permit of a sufficiently wide range of motion for pawl 16. Considering the position assumed by the brushes during each of these successive long steps of the 95 shaft 4, it is to be understood that the ratchet teeth 13 are so spaced on the rack 11 that when one impulse traverses primary magnet PM and pawl 16 is actuated to give shaft 4 one long step, the brushes 8, 9, 10 are brought into operative position below the first group of trunk terminals in the upper section of the bank. When two impulses are delivered to magnet PM and the shaft takes two long steps, the brushes 5, 6, 7 are positioned in operative relation to the first group of terminals in the lower section of the bank. If three impulses are sent

the brushes 8, 9, 10 are operatively positioned with respect to the second terminal group in the upper section. And if four impulses are sent, brushes 5, 6, 7 are positioned 5 below the second group in the lower section. In a similar manner, for as many groups as may be contained in each section, an odd number of impulses operates to place 10 brushes 8, 9, 10 below the corresponding group in the odd section, while an even number of impulses operates to position brushes 5, 6, 7 below the corresponding group in the even section. In accordance with the above 15 described operation of the switch shaft and its associated brushes, and assuming for example the switch shown is one of a number of selectors in a 1000 line exchange, all groups of trunks having access through succeeding connectors to lines with telephone 20 numbers having an odd first digit are arranged in the upper section of the selector bank. On the other hand, all trunk groups representing lines with an even first digit number are arranged in the lower section.

25 A secondary stepping magnet SM has an armature 17 pivoted at 18, and provided at its free end with a pawl 19. For each impulse traversing magnet SM armature 17 is attracted and thereby moves the pawl 19 30 into engagement with one of the closely spaced ratchet teeth 12 to move the shaft one short or trunk hunting step. For each short step thus taken the particular set of brushes that was previously positioned below a 35 group of terminals is moved up over the successive terminals in such group in search of an idle trunk. A pair of interrupter springs 20 and 21 is normally held in a circuit closing position by armature 17, but 40 upon the attraction of said armature, springs 20 and 21 are opened to interrupt a circuit for the secondary magnet as will later appear.

45 A pawl 22 is pivoted to the free end of armature 70 and normally rests in engagement with the ratchet teeth 12 to maintain shaft 4 in its actuated position. Armature 70 is controlled by a release magnet RM, which upon energizing attracts the same to 50 withdraw the holding pawl, thereby allowing the brush shaft to restore to its normal position. Relays 23 and 24 are each composed of two windings. Said relays are wound so that the magnetizing effect of one 55 coil is differential to that of the other. That is to say, if current flows in one coil of either of said relays the resultant magnetization is sufficient to attract its armatures, but if current flows through both windings of 60 either of said relays the magnetizing effect of one winding neutralizes that of the other and the armatures are not attracted.

65 From the above description it is obvious that the selector switch taken to illustrate the invention is designed to operate on the

long and short step principle. However, it is to be understood that the said invention, which consists in the provision of means for the selection of one or another of a plurality of simultaneously actuated sets of 70 brushes, according as the conditions require, is not limited to the particular type of switch shown.

Having explained in general the elements comprising the illustrated embodiment, a 75 more detailed description will now be given of the process involved in extending a call from a substation through the selector switch shown.

Consider that the subscriber at substation 80 1 desires to communicate with some other subscriber having a telephone number the first digit of which is an odd number, as for instance the digit 5. By removing the receiver from the hook a circuit is completed 85 to start an idle finder or other preliminary switch in operation. Such switch, being well understood, is not shown in the figure. The preliminary switch upon making connection with the terminals of the calling line 90 extends the same over the trunk 25, 26, to close a circuit for line relay 3 of the selector switch. This circuit may be followed from free pole of battery, left-hand winding of relay 3, first position contact and side-switch 95 arm 27, trunk conductor 25, through the preliminary switch, over the loop of substation 1, back through the preliminary switch, trunk conductor 26, side-switch arm 28 and its first position contact, right-hand winding 100 of relay 3, to ground. Relay 3 by attracting its armature closes the following circuit: ground, side-switch arm 29 and its first position contact, armature and front contact of relay 3, conductor 30, winding of slow-to-release relay 31, to battery and ground. 105

The energization of relay 3 also establishes the following circuit for the left-hand winding of differential relay 23: ground, side-switch arm 29 and its first position contact, 110 armature and front contact of relay 3, conductor 32, outer left-hand armature and contact of the differential relay 24, left-hand winding of relay 23, to battery and ground. Relay 23 energizes in this circuit to attract 115 its armatures, and thereby closes a locking circuit for itself as follows: free pole of battery, left-hand winding, contact and left-hand armature of relay 23, conductor 33, to ground at the right-hand armature and contact of slow-to-release relay 31. 120

The calling subscriber now operates the sender 2 to transmit a series of impulses corresponding to the first digit of the desired number, or as assumed, five impulses. At 125 the first opening of the line by sender 2, relay 3 retracts its armature to close a circuit for a second slow-to-release relay 34, traceable from ground side-switch arm 29 and its first position contact, armature and back con- 130

tact of relay 3, conductor 35, left-hand armature and front contact of relay 31, winding of relay 34, to battery and ground. Relay 34 attracts its armature to establish a circuit 5 for the escape magnet 36, from ground, armature and contact of relay 34, first position contact and side-switch arm 37, winding of magnet 36 to battery. The escape magnet controls the side switch and is designed to 10 step the same from first to second positions by deenergizing. It will be noted that the circuit of relay 31 is opened by the retraction of the line relay armature, but being slow to release it holds its armature, and thereby 15 maintains the previously traced locking circuit for the differential relay 23 during the short interval relay 3 is deenergized. Another circuit is established by the retraction of the line relay's armature, traceable 20 from ground, side-switch arm 29 and its first position contact, armature and back contact of relay 3, conductor 35, left-hand armature and front contact of relay 31, conductor 38, first position contact and side-switch arm 39, 25 winding of the primary stepping magnet PM, to battery and ground. Said stepping magnet by energizing gives the shaft 4 one long step and places brushes 8, 9, 10 below the first group in the upper section of the 30 bank.

Still another circuit is completed by the deenergization of the relay 3 in response to the first interruption of the line. This circuit leads from ground, side-switch arm 35 29 and its first position contact, armature and back contact of relay 3, conductors 35 and 40, outer right-hand armature and front contact of relay 23, left-hand winding of relay 24, to battery and ground. 40 Relay 24 energizes in this circuit and attracts its armatures. Thereupon a holding circuit is completed for said relay as follows: battery, left-hand winding, contact and inner left-hand armature of relay 24, 45 conductor 33 to ground at the right-hand armature and contact of relay 31. As soon as the line is again closed by sender 2 at the completion of the first impulse relay 3 attracts its armature to close a circuit 50 from ground, side-switch arm 29 and its first position contact, armature and front contact of relay 3, conductor 32, outer left-hand armature and front contact of relay 24, contact and inner right-hand armature of relay 23, right-hand winding of relay 23, to 55 battery and ground. Current flowing in this winding of relay 23 neutralizes the effect of the other winding, thereby permitting the armatures to retract, which in turn 60 severs the circuits of both of said windings. Thus at the end of the first impulse of the group selecting series, we find that one operating impulse has been delivered to the primary circuit to place brushes 8, 9, 10 65 below the first terminal group in the odd

group section, and that the condition of differential relays 23 and 24 is as follows: The circuits of both windings of relay 23 are open and therefore the armatures are in their retracted position. The left-hand winding of relay 24 is energized and its circuit locked as above explained. Hence the armatures of this relay are in their attracted position.

The second opening of the line, immediately following the first, causes line relay 3 to deenergize and release its armature as before. This sends a second operating impulse to primary magnet PM over the previously traced circuit. Another circuit is 75 also completed at the same time from ground, side switch arm 29 and its first position contact, armature and back contact of relay 3, conductors 35 and 40, outer right-hand armature and back contact of 80 relay 23, contact and innermost right-hand armature of relay 24, right-hand winding of relay 24 to battery and ground. Current flowing in this winding of relay 24 neutralizes the magnetization of the left- 85 hand winding and the relay permits its armatures to retract to their normal positions. As soon as the line closes at the end of the second interruption by the sender, line relay 3 attracts its armature and the 90 following circuit is completed: ground, side-switch arm 29 and its first position contact, armature and front contact of relay 3, conductor 32, outer left-hand armature and back contact of relay 24, left-hand 95 winding of relay 23, to battery and ground. Relay 23 energizes in this circuit, attracts its armatures, and locks up over the previously traced circuit to ground at the right-hand armature and contact of slow- 100 to-release relay 31.

Two impulses of the group selecting series have now been sent with the result that magnet PM has given the shaft 4 two long steps to position brushes 5, 6, 7 below the first 110 trunk group in the lower section of the bank. As to relays 23 and 24, we find that their condition is the same as when the relay 3 first energized at the time the selector switch was taken for use by the initiation of the call. 115 That is, both windings of relay 24 are in open circuit, while relay 23 has its armature attracted due to the energization of its left-hand winding. Therefore, when the third opening and closure of the subscriber's line 120 occurs for the purpose of sending the third impulse the operation of relays 23 and 24 is precisely the same as that resulting from the first opening and closure. Said third impulse operates to energize magnet PM 125 as before, whereby shaft 4 positions brushes 8, 9, 10 below the second terminal group in the upper section. By analogy to the foregoing it is apparent that an odd number of impulses sent out by the calling sub- 130

scriber serves to step brushes 8, 9, 10 into operative relation to one of the groups in the upper section. And furthermore relays 23 and 24 respond directly to said odd numbered series of impulses so that at the cessation thereof relay 24 is in its attracted condition. But if the subscriber sends an even number of impulses, brushes 5, 6, 7 are brought into operative relation to one of the groups in the lower section. And relays 23 and 24 respond directly to said impulses so that at the end thereof relay 24 is in its normal retracted condition.

In the case assumed, where the subscriber 15 at station 1 wishes to converse with some other subscriber whose number has five as its first digit, the transmission of the five impulses serves to move brushes 8, 9, 10 five long steps and brings them to rest below the 20 third group in the upper section, this being the fifth hundred group. An odd number of impulses having been sent relay 24 holds its armatures attracted. This connects the conductors 41 and 42 to the line brushes 9 and 25 10 respectively over the two outermost right-hand armatures of relay 24.

At the termination of the group selecting impulse series the line relay 3 holds its armature, causing an interruption in the circuit 30 of relay 34 for a sufficient period to permit the latter to deenergize. Relay 34 by retracting its armature severs the escape magnet circuit and the side switch is stepped to second position. In this position a circuit is 35 closed from ground, side-switch arm 43 and its second position contact, interrupter springs 21 and 20, winding of the secondary stepping magnet SM, to battery and ground. Magnet SM interrupts its own circuit and 40 steps the brushes 8, 9, 10 over the terminals of the selected group.

Idle trunks are those having a ground potential on the test terminal thereof. Assume the trunk 44, 45, 46 to be the first idle one 45 encountered in the group. When test brush 8 strikes the terminal of test conductor 44, the following circuit is closed: grounded conductor 44, test brush 8, conductor 47, front contact and next to the innermost 50 right-hand armature of relay 24, conductors 48 and 49, second position contact and side switch arm 37, escape magnet 36, to battery. Said escape magnet being so designed, steps the side switch into third position on energizing. This opens the circuit of magnet 55 SM and stops the brushes on the idle trunk terminals. The calling line is now extended over side-switch wipers 27, 28, conductors 41, 42, the two outermost right-hand armatures and front contacts of relay 24, conductors 50, 51, brushes 9, 10, to the idle trunk conductors 45, 46. In any well known manner the idle ground may be removed from the trunk 44 by the operation of apparatus 60 associated with the next succeeding switch

in the system so that all multiples of said trunk will test busy to other selectors.

When side-switch wipers 27 and 28 leave position 2, line relay 3 deenergizes, and in turn causes relay 31 to retract its armatures. 70 At its right-hand armature relay 31 opens the above described holding circuit for relay 24. But the relay 31 being slow to release does not sever such circuit until after side-switch arm 29 has arrived in its third position to substitute a new holding circuit for the relay 24.

At the end of the conversation and when the receivers are replaced, the idle ground potential again appears on the test conductor 44. A circuit may thereupon be traced from grounded conductor 44, brush 8, conductor 47, front contact and next to the innermost right-hand armature of relay 24, conductor 48, third position contact and side-switch arm 52, conductor 53, off-normal contacts 57 and 58 winding of release magnet RM, to battery and ground. Magnet RM attracts its armature 70 to withdraw pawl 22 and allow the switch to restore to normal. 80 Armature 23 also closes a locking circuit to insure a complete release of the brush shaft as follows: battery, winding of magnet RM, conductor 56, off-normal contacts 58 and 57, contacts 54 and 55, to ground. 85

Should the subscriber at substation 1 desire to communicate with a subscriber whose number has an even first digit, he sends an even numbered series of group selecting impulses to step the brushes 5, 6, 7 below the 90 corresponding terminal group in the lower section. In this case relay 24 is in its normal retracted condition at the end of said impulses and conductors 41, 42 are therefore extended by way of conductors 59, 60 to line 105 brushes 6 and 7 respectively.

What is claimed is:

1. In a telephone system, a switch having a plurality of sets of brushes, a line, a plurality of impulse circuits, a relay for sending impulses simultaneously over each of said circuits, means for actuating said relay, means operated by the impulses sent over one of said circuits for actuating said brushes, and means operated by the impulses sent over the other of said circuits for successively establishing and disestablishing a connection between said line and each of said sets of brushes. 110

2. In a telephone system, a selective switch 120 having terminal groups, said groups being arranged in sets, a plurality of sets of brushes, each one coöperating with a different set of said groups, a line, impulse circuits, a relay associated with said line for sending impulses simultaneously over said circuits, means for sending impulses over said line to actuate said relay, means operated by the impulses in one of said circuits for actuating said brushes, and means op- 125 130

- erated by the impulses in the other of said circuits for successively establishing and dis-establishing a connection between said line and each of said sets of brushes. 50
- 5 3. In a telephone system, a subscriber's station, a selective switch having groups of terminals, said groups being arranged in sets, a plurality of sets of brushes, each one coöperating with a different set of said 55 groups, a plurality of impulse circuits, a relay for sending impulses over said circuits simultaneously, means for actuating said relay from the subscriber's station, means responsive to the impulses in one of 60 said circuits for actuating said brushes, and means responsive to the impulses in the other of said circuits for successively rendering effective and ineffective each of said sets of brushes. 65
- 10 4. In a telephone system, a subscriber's station, a selective switch having terminal groups, said groups being arranged in sets, a plurality of brush sets, each one coöperating with a different set of said groups, 70 impulse circuits, a relay for sending series of impulses over said circuits, means for actuating said relay by impulses sent from the subscriber's station, means operated by the impulses in one of said circuits for actuating said brushes, and a plurality of relays operated by the impulses in the other impulse circuits for successively rendering effective and ineffective each of said sets of brushes. 75
- 15 5. In a telephone system, a subscriber's station, a selective switch having groups of terminals, said groups being arranged in two sections, a pair of brush sets in fixed relation with each other, one set for each 80 section of terminal groups, impulse circuits, impulse mechanism in one of said circuits for moving said brushes over said terminal groups, a differential relay in the other of said circuits for successively rendering effective each set of brushes as such set is moved into operative relation to said groups, a relay for sending impulses over said circuits simultaneously, and means for actuating 85
- 20 said last relay by impulses sent from the subscriber's station. 90
- 5 6. In a telephone system, a subscriber's station, a selective switch, two series of terminal groups for said switch, a pair of sets of brushes coöperating therewith, one set for each series, impulse operated mechanism for moving said brushes simultaneously, means for sending impulses to said mechanism from the subscriber's station, and a differential relay directly responsive to said impulses for rendering effective each 60 set of brushes as such set is moved into operative relation to the successive terminal groups. 65
7. In a telephone system, a subscriber's station, a selective switch, series of groups 70 of terminals for said switch, a plurality of sets of brushes in a fixed relation to each other, one set for each of said series of groups, impulse operated mechanism for moving said sets of brushes, means for sending impulses to said mechanism from the subscriber's station, and a differential relay directly responsive to said impulses for rendering each set of brushes effective as such set is moved into operative relation to the 75 successive terminal groups. 80
- 25 8. In a telephone system, a subscriber's line, a selective switch having two series of terminals arranged in groups, a pair of sets of brushes coöperating therewith, one set for each series, impulse operating mechanism for moving said brushes simultaneously to select a desired one of said groups, means for sending impulses to said mechanism over the subscriber's line, and a differential 85 relay responsive to said impulses for successively rendering effective each set of brushes to extend said subscriber's line to the set of brushes having access to the selected group of terminals. 90

In witness whereof we hereunto subscribe our names this 8th day of September, A. D., 1917.

HENRY P. CLAUSEN.
CHARLES L. GOODRUM.
